LUTHER X. FOSTER, OF NEW YORK, N. Y.

INTERNAL-COMBUSTION TURBINE.

1,287,277.

Specification of Letters Patent. Patented Dec. 10, 1918.

Application filed July 7, 1915. Serial No. 38,401.

To all whom it may concern:

Be it known that I, LUTHER X. FOSTER, a citizen of the United States, residing in the city of New York, borough of Queens, county 5 of Queens, and State of New York, have invented a certain new and useful Internal-Combustion Turbine, of which the following is a specification.

This invention is an internal combustion 10 turbine, and the object of the invention is the provision of a device of this class which will be extremely simple in construction and operation, positive in its action, and of maximum efficiency.

The present invention embodies many improvements over the rotary engines heretofore suggested, among which improvements may be mentioned, first, the forming of the structure in such manner that a cooling current 15 may be passed about all the movable parts for the purpose of precluding overheating; second, the particular formation of the rotor which effectually precludes leakage; third, the formation of the rotor in such manner as to allow of the application 20 of piston rings thereto to further preclude leakage and loss of power; fourth, the controlling of the feed of motive fuel to obviate excess speed; fifth, the governing of the 25 compression piston directly from the rotor; sixth, the governing of the firing circuit by the compression piston, and, seventh, the compression of the motive fuel by the compression piston directly within the firing 30 pocket of the rotor.

In one of its practical forms, the invention embodies a casing interiorly of which is mounted a rotor provided with a plurality of pockets or explosion chambers and on said 35 casing is mounted a spring-controlled piston governed by the circumference of the rotor whereby, when a pocket comes in juxtaposition with the piston, the spring forces the piston into the pocket for the purpose of compressing an explosive charge previously fed into said pocket. Means are provided 40 for firing the charge immediately after compression, and the rotation of the rotor forces the piston back to its initial position. Means 45 are also provided for circulating a cooling fluid about the movable parts for the purpose of precluding overheating, and further means are employed for governing the feed of explosive mixture to the turbine, whereby 50 excess speed is precluded.

Features of the invention, other than those

specified, will be apparent from the herein-
after detailed description taken in conjunction with the accompanying drawings.

In the accompanying drawings, I have 60 illustrated one practical form of the invention, but the construction shown therein is to be understood as illustrative, only, and not as defining the limits of the invention.

Figure 1 is a central section taken on line 65 1—1 of Fig. 2.

Fig. 2 is a transverse section taken on line 2—2 of Fig. 1; and

Fig. 3 is a perspective detail section of a portion of the rotor, showing the manner in 70 which piston rings may be applied thereto.

Referring to the drawings, A indicates a power shaft on which is fixedly mounted a rotor B. Rotor B is circular in shape and embodies a peripheral annulus C of substantially circular cross-section, supported on shaft A by an integral web β . The rotor is inclosed within a casing D, formed with a water-jacket d , and an interior portion e of the casing is shaped to conform to and intimately contact with rotor B. Shaft A is rotatably supported within casing D so that the rotor is free to revolve therein.

The water or other cooling fluid which is circulated through the jacket, in a manner 85 hereinafter more fully described, is precluded from coming into contact with annulus C of the rotor by the intimate contact between portion e of the casing and the rotor, and leakage is further precluded by 90 forming lateral flanges c' upon the web of the rotor and inserting expansion rings c'' in grooves formed in flanges c' and the portion e of the casing, all as clearly shown in Figs. 1 and 2. It will thus be noted that the annular portion C of the rotor is completely housed within a correspondingly shaped chamber E within the casing.

The annular portion C of the rotor is provided on its periphery with a plurality 100 of pockets F, which constitute the firing chambers of the turbine.

In the embodiment of the invention shown the rotor is adapted to rotate in counter-clockwise direction as shown in Fig. 1 105 and, for reasons hereinafter manifest, each pocket is provided with a curved face which forms an easy slope out to the periphery of the rotor. This slope f forms a cam surface for actuating the compression piston next 110 to be described.

Positioned radially of the rotor and be-

yond the circumference thereof, a piston chamber or cylinder G is formed in casing D, and interiorly of this cylinder is positioned a piston H. Piston H is provided with a stem h, which extends through a cap g threaded upon the casing and forming the cylinder-head of cylinder G. Intermediate the piston and the cylinder-head is positioned a spiral spring g' which normally serves to depress the piston, and the lower end of said piston is shaped to enter any one of pockets F of the rotor, when said pockets are brought into juxtaposition with said piston, as shown in Fig. 1. If the rotor is moved in counter-clockwise direction from the position referred to, it will be obvious that the cam surface f of pocket F, into which piston H is projecting, will exert an upward force upon said piston to return it to its normally elevated position.

In Fig. 1 it will be noted that pockets F are of such extent as not to be entirely occupied by the piston when in its depressed position, but that a fair portion of said pocket will be left unobstructed. It is in this portion of the pocket that the motive fuel, after being compressed, is fired, and this firing is accomplished through the medium of a spark plug I which projects inwardly through the wall of the casing D, the portion e of the casing, and into a chamber i in juxtaposition with the unobstructed portion of firing pocket F.

The operation of the device as thus far described is as follows: Assuming that rotor B is turning in a counter-clockwise direction, each pocket, as it approaches the region of piston H, passes an inlet duct J which is in communication with a carburetor, not shown. Thus, as each pocket passes inlet duct J, motive fuel is fed into said pocket preferably under slight pressure. As the rotor continues its travel, the pocket is almost immediately thereafter brought into juxtaposition with piston H, whereupon spring g', which is under tension, forces piston H into said pocket, with the result that the motive fuel therein is compressed. As soon as the compressing action of the piston is completed, an electric current is passed through the spark plug I, thereby firing a charge. The firing of the charge accelerates the movement of the rotor by creating a pressure against the piston, and the cam surface f of the pocket in which the charge has been fired forces piston H upwardly as said cam surface traverses the lower face of said piston, so that, by the time said pocket has been moved to a position beyond the piston, said piston will have been raised to its elevated position and, as the rotor continues to turn, the lower face of said piston will ride upon the circumference of annular member C of the rotor, until the next pocket comes into position for compression and firing. The

gases act to drive the rotor so long as the piston remains in the pockets F. During this time, following the ignition, the gases expand and do work between the forward face of the pocket and the relatively stationary piston. However, after the piston leaves the pockets F, the gases no longer do work in the pockets, but are carried around to the exhaust port and there discharged. In this manner successive expansions impart successive impulses to the rotor as the pockets pass by the piston H.

To obtain the best results, the firing should occur at the instant piston H has completed its compression stroke and, to insure this, the electric circuit i', through which current is fed to the spark plug I, is provided with a circuit closing switch L, which is controlled by the piston itself. Switch L may be of any desired form, but is here shown as embodying a pair of spaced spring contacts l l', which are mounted upon a block of insulation l². Block of insulation l² is mounted upon cylinder-head g, and contacts l l' project inwardly into close proximity with the piston stem h. Stem h projects through the piston-head, and an insulated disk h' is secured thereon by means of a nut h². Spring contacts l l' are normally spaced apart, but the relation between them and the insulated disk h' of the piston stem is such that, when piston H descends, disk h' will contact with contact l and for the same into engagement with contact l', as clearly shown in Fig. 2. In the circuit i' is included the usual source of electrical supply i² and coil-box i³, the circuit being grounded to the casing so that, as the piston is forced down into one of the pockets F under the action of spring g', for the purpose of compressing the charge, said charge will be fired at the instant the piston reaches the end of its downward travel.

The exhaust of the spent gases or products of combustion is accomplished through an exhaust port M, which is shown as positioned diametrically opposite from piston H, i. e., at the bottom of the housing. Thus, as the rotor revolves, each pocket F is brought, subsequently to the firing operation, into juxtaposition with the exhaust port M, and the waste products of combustion are discharged.

It is essential, in securing maximum efficiency of a machine of this character, to preclude all leakage of gases. Leakage is precluded between annular member C of the rotor and the interior of the casing, by means of the intimate relation which casing portion e bears to the rotor and, moreover, by the rings c² which are positioned between these parts. Leakage is precluded between the several pockets F by placing piston rings N between adjoining pockets in such manner as to embrace the annular portion C of the

rotor. These piston rings are positioned in grooves *n* formed in the surface of member *C*, as clearly shown in Fig. 3, and are of a resilient nature, thereby causing them to 5 contact with the interior of chamber *E*.

It will thus be apparent that the particular formation of the rotor disclosed has many advantages, in that it allows of the placement thereon of rings *N*, as well as rings *c²*. The 10 great difficulty with prior art devices of this class was that leakage could not be prevented and, consequently, no appreciable amount of compression could be obtained. Thus, by the formation of the device of the 15 present invention as described, the apparently insurmountable disadvantage prevalent in the prior art devices is obviated in a simple and expeditious manner.

Another feature of the present invention 20 resides in the fact that the speed of the turbine is automatically controlled. This is accomplished by associating a fly-ball governor *O* with shaft *A*. With said governor co-operates a lever *o*, pivoted at *o'*, and 25 engaging at its opposite ends with the stem *p* of the valve *P* included in the motive fuel supply pipe *p'* which leads to the carburetor. Thus, if the turbine acquires a speed greater than that predetermined, governor *O* automatically 30 operates to diminish or entirely shut off the supply of motive fuel. However, when the turbine slows up again, governor *O* automatically reopens the valve. Thus, a constant and unvarying speed is 35 maintained, and this may be further assured by the positioning of a fly-wheel *Q* upon shaft *A* of the rotor.

As heretofore stated, means are provided 40 for precluding the over-heating of the parts during operation, and this means is shown as a device for passing a cooling fluid through the casing and interiorly of the rotor. Shaft *A* passes through substantially the center of the casing and, at one 45 side of the rotor, said casing is formed with an inwardly projecting wall *r*, the inner edge of which is substantially in contact with web *b* of the rotor. Wall *r* is substantially circular and, intermediate the outer 50 wall of the casing and the rotor, a partition *r'* is positioned, thereby dividing the space within wall *r* into two chambers *s* *s'*. In the chamber *s'* adjacent the rotor is positioned a centrifugal pump *S* fixed on the 55 shaft and provided with a plurality of blades *s²*, as is common in centrifugal pumps of this character. The cooling fluid, such, e.g., as water, is admitted into the chamber *s* through an inlet pipe *T* and finds its way 60 into the pump through an inlet port *t*, near the center of the pump. The outlet from the pump is designated in the drawings by the reference numeral *t'* and is shown in the form of a port in the wall *r* on the opposite 65 side of shaft *A* from inlet port *t*.

The operation of the pump will be obvious, but may be briefly stated as follows: The cooling fluid is fed through pipe *T* into chamber *s*, and passes through inlet port *t*, into the interior of pump *S*. Wheel *S*, being fixed on shaft *A*, rotates with rotor *B*, and the cooling fluid thus emanates from outlet port *t'* into the casing of the turbine. 70

The casing is shown in the drawings as divided, in a plane perpendicular to the axis of rotation of the rotor, into two parts, which are secured together by means of bolts *a* or other equivalent devices, and the cooling fluid fed into one lateral half of the casing passes through apertures *a'* in the adjoining parts of the casing into the other lateral half thereof, to be subsequently discharged from outlet pipe *T'* at the upper portion of the casing. As long as the rotor is operating, the pump is also actuated and, consequently, a constant circulation of cooling fluid is passing through the casing and coming into intimate contact with the parts subjected to the heat of operation, as will be clearly apparent from Fig. 2 of the drawings. Attention may here again be directed to rings *c²* hereinbefore described, as it will be manifest that these rings have the further function of precluding the cooling fluid from leaking into the explosive pockets of 95 the rotor.

The turbine is provided with a suitable support or standard *N* to maintain the device in proper operative position, but this supporting means may be of any desired 100 character, depending, of course, on the use to which the machine is to be adapted.

Throughout the accompanying drawings and the foregoing description, no attempt has been made to show or describe such accessories as glands, packing boxes, and other well known devices common to all engines and these parts have been omitted in the interest of clearness. It will be manifest, however, that, if desired, shaft *A* may be 105 properly packed to preclude leakage of the cooling fluid from the casing and that suitable lubricating devices will be employed. Furthermore, suitable change speed or reverse gearing may be associated with the 110 turbine, but this forms no part of the present invention and a showing thereof is unnecessary, as the rotor may be secured directly to shaft *A* and drive the same in a 115 constant direction, all speed gearing, etc., being positioned externally of the casing, the same being of any well known, conventional type.

The embodiment of the invention illustrated is the preferred form, but, manifestly, slight changes may be made in adapting the invention to its various environments. Moreover, the invention embodies several improvements which, when used in conjunction with one another, result in a 120 125 130

machine of maximum efficiency. However, I am aware of the fact that a highly efficient machine may be constructed by employing some of the features of my invention without necessarily employing all, and I do, therefore, consider my invention to be as broadly novel as commensurate with the appended claim.

Having thus fully described the invention, 10 what I claim as new and desire to secure by Letters Patent is:

In a machine of the class described, the combination of a jacketed casing, a rotor rotatably mounted therein, said rotor being 15 provided on its periphery with a plurality

of pockets, a reciprocating piston positioned radially of the rotor and normally beyond the circumference thereof, a spring for forcing the piston successively into the pockets when the pockets of the rotor are brought 20 into juxtaposition therewith for the purpose of compressing directly within the pockets, motive fuel previously fed therewith, means for successively feeding said motive fuel into the pockets, and means controlled by 25 movement of the piston for firing said motive fuel when compressed by the piston.

In testimony whereof I have signed my name to this specification.

LUTHER X. FOSTER.
